PORTABLE ELECTRICAL OUTLET CORD REEL

Bernard J. Tamarin, Whitemarsh, Pa.
(W. Valley Green Road and Hunt Lane, Flourtown, Pa.)

Filed July 7, 1960, Ser. No. 61,263

Term of patent 14 years

(Cl. D26—1)

Fig. 1

Fig. 2

Fig. 4

Fig. 3

FIG. 1 is a perspective view of a portable electrical outlet cord reel, showing my new design;

FIG. 2 is a top plan view, to a reduced scale;

FIG. 3 is a side elevational view, the opposite side being substantially a mirror image thereof; and

FIG. 4 is a side elevational view taken at 90 degrees to that shown in FIG. 3, the opposite side being substantially shown in FIG. 1.

The bottom, not shown, has a conventional appearance.

I claim:

The ornamental design for a portable electrical outlet cord reel, substantially as shown and described.
